CATHODE RAY TUBE DEVICE

William Henry Barkow, Pennsauken, N. J., assignor to Radio Corporation of America, a corporation of Delaware

Application February 28, 1955, Serial No. 490,979

11 Claims. (Cl. 313—70)

This invention relates to systems for controlling the electron beams of cathode ray tubes and, particularly, to systems in which a plurality of beams is deflected by a common deflection apparatus.

One type of cathode ray tube with which the present invention may be successfully employed is a color kinescope of the general type described in an article titled "A Three-Gun Shadow-Mask Color Kinescope," by H. B. Law published in the Proceedings of the I. R. E., vol. 39, No. 10, October 1951 at page 1186. Such a tube has a luminescent screen as part of a target electrode in which different phosphor areas produce differently colored light when excited by electron beam components impinging upon it from different angles, the angle of impingement determining the particular color of the light produced by the phosphor areas. The invention also pertains to a kinescope of the type described in another article titled "A One-Gun Shadow-Mask Color Kinescope," by R. R. Law, published in the Proceedings of the I. R. E., vol. 39, No. 10, October 1951 at page 1194.

It is necessary for the satisfactory operation of such kinescopes to effect substantial convergence of the different electron beam components at all points of the raster scanned thereby in the plane of the target electrode. In general, this convergence may be effected by means of apparatus such as that disclosed in an article titled "Deflection and Convergence in Color Kinescopes" by A. W. Friend, published in the Proceedings of the I. R. E., vol. 39, No. 10, October 1951 at page 1249. Such beam convergence apparatus includes an electron-optical system by which to control the beam convergence angles. The electron-optical system is variably energized as a function of the radial angle of beam deflection.

Another type of apparatus for controlling the convergence of a plurality of electron beam components in a predetermined plane and with which the present invention may be employed with particular advantage, comprises, in general, means for producing a plurality of electron beam components which traverse predeflection paths that are spaced respectively about the longitudinal axis of the tube, and individual electromagnetic means located respectively adjacent to the predeflection beam paths and of such a character as to be energizable directly from the beam deflection circuits in a manner to effect the desired beam convergence. In this manner, the beam convergence angle may be varied in a manner suitable to maintain the desired beam convergence in the predetermined plane at all points in the scanned raster.

More particularly, it will be understood that the term "beam components" as used herein denotes either a plurality of individual electron beams emanating, respectively, from a plurality of electron guns or from a single electron gun provided with suitable electron-optical, or other apparatus, for forming three individual beams and, in addition, those components of a single electron beam to which is imparted a spinning motion so as to trace a substantially conic locus at different positions thereof. Accordingly, the apparatus by which a plurality of such

2

electron beam components is produced may include on the one hand, three electron guns or, on the other hand, a single electron gun, together with the auxiliary apparatus by which the spinning motion is imparted to the beam.

5 One particular beam convergence apparatus with which this invention may be advantageously employed includes for each beam component a pair of pole pieces located internally of the kinescope envelope. It has been found that magnetic flux leaking from the deflection yoke traverses the various pairs of pole pieces differently, thereby tending to cause a misconvergence of the beam components.

10 It is a primary object of the present invention to provide means for restraining the magnetic fields which ordinarily extend beyond an electromagnetic deflection yoke.

Another object of the invention is to prevent leakage flux from a raster-scanning deflection yoke from affecting beam-convergence apparatus in a manner to cause misconvergence of a plurality of beam components.

15 Still another object of the invention is to shield a plurality of individual beam-convergence electromagnets located in a predeflection region of a plurality of beam components from a raster-scanning deflection yoke.

20 In accordance with the disclosure in the H. L. Goodrich U. S. Patent No. 2,677,779, granted May 4, 1954, multi-beam cathode ray tube apparatus, having a plurality of beam convergence electromagnets located in a predeflection region of the beams, is provided with a magnetic shield located between the beam deflection apparatus and the beam convergence apparatus to exclude from the latter leakage flux from the former. Such a shield may, as stated therein, comprise a disk of high-permeability material such as ferrite.

25 Since the horizontal frequency deflection field is also capable of producing deleterious effects upon beam-convergence apparatus of that type, there is disclosed in the co-pending application of A. M. Morrell, S. N. 395,371, filed December 1, 1953, a shield designed specifically for shielding against the flux produced by the high frequency deflection coils, which shield may be of conductive material such as copper having no undesirable distorting effect upon the deflection yoke field.

30 The present invention provides improved magnetic flux-permeable means for restraining primarily the low frequency vertical deflection flux which ordinarily extends rearwardly of the deflection yoke, which means will be understood as using less axial length of the cathode ray tube than prior art devices. Moreover, the shielding means of the invention affords more uniform shielding action and with substantially no undesirable effect upon the "deflection centers" of the yoke fields.

35 In accordance with a specific form of the present invention, there is provided in conjunction with an electromagnetic deflection yoke a conductive disk (e. g. copper) for shielding the high frequency deflection flux and a pair of grain-oriented steel disk-like members whose respective directions of grain orientation are normal to each other. The conductive disk is most effective at the horizontal scanning frequency rate while the steel disks serve efficiently to restrain rearward activity by vertical deflection flux.

40 Additional objects and advantages of the present invention will become apparent to persons skilled in the art from a study of the following detailed description of the accompanying drawing in which:

45 Figure 1 is a view showing the general arrangement of image-reproducing apparatus embodying an electron beam convergence system and including shielding means in accordance with one form of this invention;

50 Figure 2 is a transverse cross-sectional view taken generally on the line 2—2 of Figure 1 and showing the

arrangement of the beam convergence electromagnets illustrated in Figure 1; and

Figure 3 is an enlarged, vertical sectional view of a portion of the apparatus of Figure 1 showing the shielding apparatus more clearly.

Reference first will be made to Figure 1 for a general description of an illustrative embodiment of electron beam convergence system in connection with which the present invention finds particular application. The system includes a tri-color kinescope 11 which may be of the same general type as that disclosed in the H. B. Law paper previously referred to. It will be understood, however, that the kinescope, alternatively, may be of other types such as that shown in the R. R. Law paper. In either case, however, the kinescope preferably has a luminescent screen 12 provided with a multiplicity of small phosphor areas arranged in groups and capable respectively of producing light of the different primary colors in which the image is to be reproduced when excited by an electron beam. In back of and spaced from the screen 12 there is an apertured masking electrode 13 having an aperture for and in alignment with each group of phosphor areas of the screen 12.

In the particular tube illustrated, the kinescope also has a plurality of electron guns, equal in number to the number of primary colors in which the image is to be reproduced. Each of these guns may be conventional, consisting of a cathode, a control grid, an accelerating grid and a focusing electrode. Since the three-guns are identical, the different parts thereof will be referred collectively as the cathodes 14', the control grids 14, accelerating grids 15, and the focusing electrodes 16. The three electron guns produce schematically represented beams 17, 18 and 19 by which to energize, respectively, the blue, red and green phosphor areas of the screen 12. When these electron beams are properly converged in the plane of the masking electrode 13, they pass through the apertures thereof from different directions and impinge upon different phosphor areas of the various groups so as to produce blue, red and green light. It is to be noted that the size of the phosphor areas, the angles between the beams and the spacing of the mask 13 from the screen 12 as compared with the length of the tube are exaggerated for better illustration of the operation of the kinescope.

The electron-optical apparatus of the kinescope 11 also includes a beam-accelerating electrode consisting, in the present instance, of a conductive wall coating 20 formed on the inner surface of the tubular neck 21 of the kinescope extending from the region adjacent to the outer end of the electrodes 16 to the conical section 22 of the tube which in this case is metallic. Suitable electrical connection (not shown) is made at the junction of the wall coating with the metal cone 22. A cylinder 20' electrically connected to the wall coating 20 also serves in the focusing of the several beams. Preferably, the target electrode structure, including the masking electrode 13 and the luminescent screen 12 which for this purpose may be metallized, is electrically connected to the metal cone 22 by suitable means (not shown). Metallization of a luminescent screen of the character described may be effected in the manner disclosed in a paper by D. W. Epstein and L. Pensak titled "Improved Cathode Ray Tubes with Metal-Backed Luminescent Screens" published in the RCA Review, vol. VII, March 1946 at pages 5-10.

The described electrode structure of the kinescope may be energized in a conventional manner such as that illustrated. The source of energy is represented by a battery 23 across the terminals of which there is connected a voltage divider 24. The cathodes 14' are connected to a point which is somewhat negative relative to ground. The accelerating grids 15 are supplied with a potential of, for example, 200 volts. Similarly, the focusing electrodes 16 are connected to a point on the voltage divider which may conventionally be at a potential of approximately

8000 volts positive relative to the grounded cathodes. Also the beam-accelerating anode, including the wall coating 20 and metal cone 22, is connected to the voltage divider 24 at a point which may conventionally be approximately 27,000 volts positive relative to the grounded cathodes.

The electron beams 17, 18 and 19 are modulated suitably in intensity under the control of color-representative video signals derived from a source 25. It will be understood that the video signal source is represented herein entirely diagrammatically since it does not form an essential part of the present invention. The signal source 25 usually will be part of a signal receiver and may be understood to include a signal detector, or equivalent device, together with one or more stages of video signal amplification. Alternatively, the video signal source may be a color television camera in the event that the kinescope 11 is employed as a monitor, for example. Also, it will be understood that the illustrated connection of the video signal source 25 to the electron guns of the kinescope 11 is merely diagrammatic and accordingly these connections may or may not be made directly to the cathodes 14'. Instead, it will be understood, that they may be made to the grids 14 or, in accordance with modes of operation of color image-reproducing apparatus, the video signal source may be connected both to the cathodes and to the control grids of the electron guns.

Also associated with the color kinescope 11 is a deflection yoke 26 which may be entirely conventional including two pairs of suitably placed coils electrically connected together in such a manner that, when properly energized, electromagnetic fields are produced, whereby to effect both horizontal and vertical angular deflections of the electron beams so as to scan the usual rectangular raster. Energization of the deflection coils comprising the yoke 26 may be effected by conventional vertical and horizontal deflection wave generators 27 and 28, respectively. Such apparatus will be understood to function suitably to produce substantially sawtooth energy at both horizontal and vertical deflection frequencies so that the fields produced by the yoke 26 are varied in a substantially sawtooth manner.

The beam convergence system also includes a plurality of electromagnetic field producing elements such as the magnets 29 and 30 mounted around the neck 21 of the color kinescope adjacent to the predeflection paths of the electron beam components. It is to be understood that the precise location of these magnets is not necessarily indicated in the figure. Instead, as will appear in greater detail, it is to be understood that each of these magnets is located relative to one of the electron beam components so as to influence its associated beam component to the substantial exclusion of the others. Furthermore, it is to be understood that these magnets are of a character which, when suitably energized, produce respective fields which are transverse to the associated beam paths.

Each of these convergence electromagnets includes a pair of spaced pole pieces and at least one energizing winding. Preferably two windings are provided for each of the electromagnets for separate energization. These features will be described subsequently in greater detail.

Before describing the details of the convergence system, a brief description will be given of the general manner in which the apparatus functions to produce the desired results. The convergence magnets such as 29 and 30 are energized by substantially unidirectional energy so as to effect an initial convergence of the electron beam components substantially in the plane of the apertured masking electrode 13. In order to do this, the unidirectional energization of these magnets is effected in such a way that the magnets may be individually energized in different magnitudes. In effecting this initial beam convergence, it is to be understood that the beam may be in any desired one of their different deflected positions. For example, they may be initially converged at the center

of the raster to be scanned. Alternatively they may be initially converged at one corner of the raster.

The convergence magnets such as 29 and 30 also are dynamically energized by the control wave energy derived from a suitable generator (not shown in Figure 1) so as to effect a variation in the magnitude of the transverse fields produced respectively thereby. These field strength variations are in accordance with a predetermined function of the beam deflection. Variations in the strength of the fields produced by the convergence magnets such as 29 and 30 effect corresponding variations in the paths of the electron beam components relative to the longitudinal axis of the tube. Hence, suitable variations are made in the convergence angles between the various beam components substantially in the plane of the masking electrode 13.

For a further description of this type of beam convergence apparatus, reference now will be made to Figure 2 of the drawings. This figure shows more clearly the relative positions of the convergence magnets, such as 29 and 30 and, additionally, 31, relative to one another and to the electron beams with which they are respectively associated. Inasmuch as all of these magnets are substantially the same, only one of them will be described in detail. The convergence magnet 29, which is associated with the blue electron beam 17, is provided with a core having a body portion 32 and two external pole pieces 33 and 34. These pole pieces are mounted so as to be in close association with the tube neck 21. Also, as indicated in Figure 1, the pole pieces extend for some distance longitudinally of the tube substantially as indicated. The magnet also is provided with an energizing coil structure 35 mounted upon the body portion 32. The energizing coil 35 preferably is provided with two windings, one for static energization and the other for dynamic energization. The convergence magnet 29 produces a field which, in the vicinity of the electron beam 17, is substantially transverse to the axis of the kinescope. By means of such a field, the electron beam 17 may be moved toward or away from the longitudinal axis. The direction and magnitude of such a beam movement is controlled by the energization of the magnet by means including the coil 35.

In Figure 2, it also is illustrated that for each of the magnets there are provided on the inside of the tube neck 21 extended pole pieces so as to increase the effectiveness of these magnets. The magnet 29, for example, is provided with a pair of inwardly extending pole pieces 36 and 37, associated respectively with the external pole pieces 33 and 34. By such means, it is seen that the reluctance of the magnetic circuit is considerably decreased, and also the flux distribution of the field produced between the internal pole pieces 36 and 37 is considerably improved.

With beam convergence apparatus of this general character, it may be seen from a further consideration of Figure 2 that such apparatus is adversely effected by both horizontal and vertical deflection flux from the deflection yoke. Leakage deflection flux of a character to deflect the electron beam components 17, 18 and 19 to the left as viewed in the drawing is indicated by the broken lines 38. With respect to the internal pole pieces 36 and 37 associated with the electromagnet 29, no adverse effects of the leakage deflection flux are produced. However, it is seen that the leakage deflection flux 38 passes between the internal pole pieces 39 and 40 of the electromagnet 30 substantially at right angles to these pole pieces since this is the path of lowest reluctance. Similarly, the leakage deflection flux 38 passes between the internal pole pieces 41 and 42 of the electromagnet 31 at right angles to these pole pieces. As a result, it may be seen that when the beams are being deflected to the left, the red beam 18 will be moved to a higher position than it would have in the absence of the leakage flux from the deflection yoke, as indicated by the arrow. Similarly, the

green beam 19 will have a lower than normal position when beam deflection is toward the left. Conversely, when beam deflection by the yoke is toward the right, as viewed in Figure 2, the leakage flux 38 will be in the opposite direction, thereby tending to move the red beam downwardly and the green beam upwardly. Consequently, there is effected a misconvergence of the electron beam components as a result of the leakage flux from the deflection yoke traversing the internal pole pieces of certain of the convergence electromagnets.

As has been stated, the present invention provides new and improved means for restraining the activity of the deflection flux of the electromagnetic yoke 26 and in a manner which prevents the deflection flux from having an undesirable effect upon the convergence magnetic fields. Moreover, the apparatus of the present invention introduces no undesirable distortion insofar as the deflection fields themselves are concerned. It has been found, in general, that a magnetic shunt of certain types of high permeability material, if used as the shielding means, may have the effect of distorting the deflection field as by "short circuiting" the field across the rear windings of the yoke, thereby shifting the center of deflection. Additionally, it is known that, since conventional horizontal and vertical deflection rates are of the order of 15,750 kilocycles and 60 cycles per second, respectively, shielding against both frequency components of the deflection field may be performed in a frequency-selective manner.

With the foregoing in mind, the apparatus provided in accordance with the present invention and illustrated in Figures 1 and 3 will now be described. The yoke 26 is, as shown, conventionally housed in a cylindrical casting of insulating material such as Bakelite and is also enclosed at its rear end by a cap member 45 also formed of insulating material. The flux shielding apparatus of the present invention is conveniently supported by the cap 45 in the following manner. A disk 48 of copper or other non-magnetic material having high electrical conductivity is supported directly against the cap 45 by means of an eyelet 50. In the interest of completeness of description, it may be noted that the rear surface of the cap 45 is provided with raised annular ridges 52 which serve to prevent mechanical vibration of the disk 48 against the cap member. The disk 48 has, as shown, a central aperture of such size as to accommodate the neck 21 of the kinescope and should be of sufficient thickness to possess the necessary mechanical strength. Before describing the remaining portion of the shielding apparatus, it will be noted that a magnetic field will produce eddy currents in a member of electrically conductive material which, in turn, will produce a reverse magnetic field (Lenz's law) to oppose the field producing them. Since the production of eddy currents is the function of the frequency of the inducing field, it will be apparent that the disk 48 will be more greatly affected by the horizontal deflection field than by the vertical field and will, therefore, be more effective as a shield against the higher frequency field.

Also supported by the cap member 45, through the agency of the eyelet 50, but spaced from the cap as by a glass cylindrical spacer 54 are two disk-like members 56 and 58 of grain-oriented silicon steel. The members 56, 58 are held in place by the upset end of the eyelet 50, which eyelet may, for example, be formed of aluminum or other non-magnetic material. In the interest of providing a complete disclosure, it will be noted that the silicon steel members 56 and 58 may be formed of Tran-Cor (Armco Steel Corp.) XXX steel. The disk-like members are also formed, as shown, with central apertures of sufficient diameter to accommodate the neck of the kinescope.

Before describing the action of the shield apparatus including the copper disk 48 and the grain-oriented steel disks 56 and 58, certain characteristics of the magnetic shielding materials should be noted. While the

copper disk 48 does have a certain shielding effect insofar as the low frequency vertical deflection flux is concerned, means for additionally shielding the vertical deflection flux is required. A basic requirement for such additional shielding means is that the material employed have relatively high magnetic permeability. It has been found that most high permeability materials are more expensive than that employed in accordance with the present invention, are fragile and, therefore, subject to cracking and may also exhibit varying permeability in different portions of a disk formed thereof. In order to overcome such factors, the present invention employs as the shield which acts in conjunction with the copper shield disk-like members of grain-oriented steel. That is to say, grain-oriented steel has been found to possess a high degree of magnetic permeability in the direction of the grain. It will, therefore, be apparent that a single disk of such material, as disposed between the deflection yoke and convergence magnets and with the direction of its grain orientation parallel to the lines of magnetic flux to be shielded, a high degree of such shielding could be obtained. It has also been found, however, that such an arrangement is undesirable by reason of the fact that there would result a "shortening" of one of the deflection fields with respect to the other, which selective shortening would have an undesirable distorting effect upon raster deflection and of a type which causes misconvergence of the electron beam components, particularly in the corners of the raster. Stated otherwise, the use of a single grain-oriented steel disk member for shielding would have a tendency to warp the deflection field in the direction of the grain-orientation.

Hence, in accordance with the present invention, the grain-oriented steel disk members 56 and 58 are disposed relative to each other in such manner that their respective grain orientations are at right angles. That is to say, the disk 56 is maintained with respect to the disk 58 so that the direction of grain orientation of the former is perpendicular to the direction of the grain orientation of the latter. In order to simplify the assembling of the disks, they may be provided during manufacture with notches 56' and 58', respectively the notches being indicative of the direction of grain orientation. Thus, when the disks are assembled so that the notches of the disk 56' lie along a line which is at right angles to the notches 58' of the disk 58, the desired relative orientation of the disks is automatically achieved. The particular orientation of the disks with respect to the deflection yoke is, however, not critical.

By virtue of the employment of the two disks with their grain orientations at right angles to each other, the direction-sensitive permeability of either one of the disks is effectively eliminated, so that, as the disks 56 and 58 serve to "shunt" the deflection flux from the yoke, no undesirable direction-sensitive distortion is produced in the deflection field. Moreover, the two disks in combination afford a greater degree of shielding than that which a single disk of the same thickness can provide.

By virtue of the presence of the copper disk 48, the distance of the steel disks 56 and 58 from the yoke is rendered less critical than would be the case in the absence of the copper disk. The length of the spacer elements 54 may be determined experimentally to suit the requirements of different situations involving different yoke structures and the like. In accordance with one specific arrangement successfully employed, the spacers 54 (four in number, for example) separate the disk 56 from the disk 48 by $5\frac{1}{16}$ -inch. It has been shown experimentally that the spacing of the steel disks from the yoke is rendered even less critical when the copper disk 48 is of greater diameter than the steel disks, which fact indicates that it is preferable to employ a copper disk of greater diameter than the steel disks. It is also to be noted that the use of perpendicularly disposed, grain-oriented steel disks precludes any undesirable foreshorten-

ing of the deflection fields such as would result in an undesired shift of the respective horizontal and vertical deflection centers, which centers should coincide with the "color centers," as will be understood.

5 While the invention has been described in accordance with a specific embodiment employing grain-oriented silicon steel as the material of a pair of disk-like members disposed at right angles to each other, suitable modifications may be made in accordance with the principles of the invention. For example, four such disk-like members arranged with their directions of grain orientation displaced 90° may be employed to provide even greater shielding action.

10 Having thus described my invention, what I claim as new and desire to secure by Letters Patent is:

1. In a cathode-ray tube image reproducing system wherein an electron beam component which, after traversing a predeflection region is angularly deflected both horizontally and vertically at substantially different rates by electromagnetic beam deflection apparatus to scan a rectangular raster; apparatus located between said predeflection region and said electromagnetic apparatus for excluding deflection flux from said region, which comprises: a pair of grain-oriented steel disk members mounted externally of said tube and having a central aperture of suitable dimensions to accommodate said tube, said disk members being disposed such that the directions of orientation of their grain structures are substantially perpendicular.

20 2. In a cathode-ray tube image reproducing system wherein an electron beam component which, after traversing a pre-deflection region is angularly deflected both horizontally and vertically at substantially different rates by electromagnetic beam deflection apparatus to scan a rectangular raster; apparatus located between said predeflection region and said electromagnetic apparatus for excluding deflection flux from said region, which comprises: a disk-like member of non-magnetic material having high electrical conductivity mounted externally of said tube and having a central aperture of suitable dimensions to accommodate said tube; and first and second disk-like members of grain-oriented steel mounted externally of said tube, each having a central aperture of suitable dimensions to accommodate said tube, said first and second disk-like members being located on the side of said first member remote from said beam deflection apparatus and being disposed with their respective grain orientation directions at right angles to each other.

30 3. The invention as defined by claim 2 wherein said first-named disk-like member is of greater external dimensions radially of said tube than said steel members.

4. In a cathode-ray tube image reproducing system, wherein an electron beam component which, after traversing a pre-deflection region is angularly deflected both horizontally and vertically at substantially different rates by electromagnetic beam deflection apparatus to scan a rectangular raster; apparatus located between said predeflection region and said electromagnetic apparatus for excluding deflection flux from said region, which comprises, a disk-like member of non-magnetic material having high electrical conductivity mounted externally of said tube and having a central aperture of suitable dimensions to accommodate said tube; and first and second disk-like members of grain-oriented steel mounted externally of said tube and disposed with their respective directions of grain orientation at right angles to each other, said disk-like steel members being spaced from and located on the side of said first member remote from said beam deflection apparatus.

50 5. In a cathode-ray tube image-reproducing system wherein a plurality of electron beam components, which traverse pre-deflection paths that are spaced respectively about the longitudinal axis of the tube, are angularly deflected both horizontally and vertically at high and low frequencies, respectively, by electromagnetic beam de-

lection apparatus to scan a raster in a predetermined plane, electron beam convergence apparatus comprising, a plurality of electromagnets respectively mounted adjacent to said pre-deflection beam paths and energizable to produce respective fields transverse to said beam paths, each of said electromagnets having a core including a body portion located externally of said tube and a pair of pole pieces located internally of said tube and respectively extending from points adjacent to opposite ends of said body portion into the region of said associated beam component; a non-magnetic shield of electrically conductive material located between said deflection apparatus and said convergence electromagnets to exclude high frequency deflection flux from said electromagnets; and a pair of shield members of grain-oriented steel located between said non-magnetic shield and said convergence electromagnets and disposed with their directions of grain orientation normal to each other.

6. Electron beam convergence apparatus as defined in claim 1 wherein, said non-magnetic shield and said magnetic shield comprise disk-like members.

7. Electron beam convergence apparatus as defined in claim 6 wherein, said disk-like member of non-magnetic material is of greater dimension radially of said tube than said magnetic member.

8. Shielding apparatus for use in conjunction with an electromagnetic yoke of the type made up of horizontal and vertical deflection windings for producing electromagnetic deflection fields of substantially different frequencies, said apparatus comprising: first and second disk-like members of grain-oriented magnetic material secured with their respective directions of grain orientation at right angles to each other; and means for supporting said disk-like members at one end of such yoke.

9. Shielding apparatus for use in conjunction with an

35

electromagnetic yoke of the type made up of horizontal and vertical deflection windings for producing electromagnetic deflection fields of substantially different frequencies, said apparatus comprising: a disk-like member of non-magnetic, electrically conductive material; first and second disk-like members of grain-oriented magnetic material secured with their respective directions of grain orientation at right angles to each other; and means for supporting said disk-like members at one end of such yoke.

10. An electromagnetic cathode ray beam deflection yoke which comprises: a pair of electromagnetic deflection windings adapted to produce magnetic deflection fields of substantially different frequencies; first and second disk-like members of grain-oriented steel arranged with their respective directions of grain orientation at right angles to each other; and means for supporting said disk-like members at one end of said windings.

11. An electromagnetic cathode ray beam deflection yoke which comprises: a pair of electromagnetic deflection windings adapted to produce magnetic deflection fields of substantially different frequencies; a disk-like member of non-magnetic, electrically conductive material; first and second disk-like members of grain-oriented steel arranged with their respective directions of grain orientation at right angles to each other; and means for supporting said disk-like members at one end of said windings, said electrically conductive member being located between said windings and said steel members.
